UNITED STATES PATENT OFFICE.

HENRY W. O'DOWD, OF PEEKSKILL, NEW YORK, ASSIGNOR TO WILLIAM M. CRANE COMPANY, A CORPORATION OF NEW YORK.

AUTOMATIC GAS-VALVE.

1,182,030.

Specification of Letters Patent.

Patented May 9, 1916.

Application filed February 27, 1909. Serial No. 480,387.

To all whom it may concern:

Be it known that I, HENRY W. O'DOWD, a citizen of the United States, and a resident of Peekskill, county of Westchester, 5 and State of New York, have invented certain new and useful Improvements in Automatic Gas-Valves, of which the following is a specification.

My invention relates to gas valves, and 10 more particularly to gas valves for use in connection with burners the supply of gas to which is automatically regulated by the placing thereon or removal therefrom of some object, as, for instance, a cooking 15 utensil.

Objects of the invention are to provide a construction of the character referred to which will reduce to a negligible minimum the amount of gas remaining in the valve 20 chamber when the valve is in its closed position; which will be proof against leakage; whose parts shall be few in number and easily accessible; and which shall be simple and durable in construction and economical 25 and efficient in operation.

These and other objects of the invention will in part be obvious and in part be made clear from the following description.

The invention consists in the novel parts, 30 improvements, combinations, and features of construction herein shown and described.

The accompanying drawings, which are referred to herein and form a part hereof, illustrate two embodiments of the invention, 35 the same serving in connection with the description herein to explain the principles of the invention.

Of the drawings: Figure 1 is a vertical central section of a valve mechanism constructed in accordance with certain features 40 of my invention; and Fig. 2 is a plan of the same taken on the line 2—2 of Fig. 1.

Referring now to the drawings in detail, the embodiment of the invention illustrated 45 comprises a casing 1 adapted to be secured in communication with a gas supply pipe and containing, preferably in its lower portion, a gas passage which, as shown, is divided by a diaphragm 2 into compartments 50 3 and 4. An important feature of the invention relates to the means for establishing and interrupting communication between said compartments. In the embodiment of the invention illustrated ports 5 and 6 are 55 preferably formed in the respective upper

portions of these compartments, a flange 7 preferably outlining one of said ports and extending slightly above the port and forming a valve seat. As shown, also, a flange 8, preferably with its upper surface in the same horizontal plane as the upper surface 60 of the flanged valve seat 7, encircles the casting 1 on its inner face.

Means are provided to operate on the valve seat 7 and thus establish and cut off 65 the supply of gas passing through the mechanism. While said means may be formed and arranged in various ways and of different materials, preferably it consists of a member consisting of a valve portion 70 proper, and an extension thereof, the whole forming a diaphragm 10, preferably of flexible material, such as leather, which extends to and is seated upon the flange 8, where, in the embodiment illustrated, it is tightly 75 engaged by a cap piece 12 of the casing, said cap piece, as shown, being exteriorly threaded to correspond with the interior threading of the upper part of said casing. Said diaphragm or valve 10 is suitably fastened to a stem 13 extending through said cap piece 12, and preferably a rigid member 14 lies above and holds the valve, when in its seated position, more closely to the seat. Preferably, also, a spring 15 is coiled about 80 85 said stem 13 and is arranged to engage said member 14 and also the lower surface of said cap piece 12, thereby keeping said valve 10 normally in closed position. It will be seen that said valve diaphragm forms the 90 upper wall of a chamber which communicates with said compartments 3 and 4 and which varies in extent with the operation of the valve, whose flexibility permits of its operation, and that said chamber, when the 95 valve is in its seated position, is of very slight volume, thus preventing the accumulation of gas and air in any material amount in said valve chamber and thus obviating the evil effects of such accumulation, such 100 as back firing. It will also be noted that as said diaphragm is tightly fastened to the flange 8, leakage into the casing above said valve is prevented. Furthermore, as will be apparent, the valve is kept always flexible 105 and in good order by its operation, and ridges and indentations, which might in time permit leakage, are avoided.

Means are provided for automatically operating the valve 10; and, while, so far as 110

certain features of my invention are concerned, any suitable means may be provided, preferably, as shown, a lever 17 is engaged by said stem at a point without the casing 5 1, said lever pivoting on the fulcrum 18. This lever 17 preferably is controlled in its operation by a nut 20, which is threaded on the stem 13 and may be adjusted at will to determine the operative position of the lever, and the extent to which the valve will 10 be opened by the lever. It will be apparent that said lever may be operated by placing thereon or removing therefrom a weight, as, for instance, a cooking or other utensil, 15 when said valve is used in connection with a stove.

It will be seen that by reason of the construction shown and described a form of valve mechanism is provided which is simple, highly efficient, and thoroughly safe; 20 and which is economical in construction and operation. Other advantages will be apparent to those skilled in the art.

It is to be understood that my invention 25 in its broader aspects is not limited to the precise construction shown nor to any particular construction by which the same has been or may be carried into effect, as many changes may be made in the details of the 30 parts without departing from the main principles of the invention and without sacrificing its chief advantages.

I claim:

1. An article-controlled valve mechanism 35 including in combination a casing provided with a gas-inlet and with a gas-outlet; a partition dividing said casing horizontally into an upper and a lower compartment; a second partition disposed in angular relation 40 to said horizontal partition and dividing the lower compartment into a gas inlet chamber and a gas outlet chamber; said horizontal partition being provided with openings communicating with the gas inlet and gas outlet chambers, respectively; a flange disposed on the upper portion of said horizontal partition adjacent said casing; a flange being also arranged around the inlet opening in said partition to form a valve 45 seat; a cap member forming a closure for the upper compartment, and having a flanged extension disposed within the casing; a flexible diaphragm secured between 50

the flanged extension of the cap-member and the flange on said partition; a plunger 55 secured at one end to said flexible diaphragm, the other end passing through said cap-member; a spring-member disposed between said cap-member and diaphragm, and normally holding said diaphragm on the valve-seat; and an article-actuated lever connected with the outer end of the plunger, for positively raising the diaphragm from the valve seat.

2. An article-controlled valve mechanism 60 including in combination a casing provided with a gas-inlet and with a gas-outlet; a partition dividing said casing horizontally into an upper and a lower compartment; a second partition disposed in angular relation 65 to said horizontal partition, and dividing the lower compartment into a gas inlet chamber and a gas outlet chamber; said horizontal partition being provided with openings communicating with the gas inlet and gas outlet chambers, respectively; a flange disposed on the upper portion of said horizontal partition adjacent said casing; a flange being also arranged around the inlet opening in said partition to form a valve 70 seat; a cap member forming a closure for the upper compartment, and having a flanged extension disposed within the casing; a flexible diaphragm secured between 75 the flanged extension of the cap-member and the flange on said partition; a plunger 80 secured at one end to said flexible diaphragm, the other end passing through said cap-member; a spring member disposed between said cap-member and diaphragm, and normally holding said diaphragm on the valve-seat; an article-actuated lever connected with the outer end of the plunger, for positively raising the diaphragm from the valve seat; and means disposed on the 85 outer end of plunger for regulating the flow of gas through said openings when the lever has been actuated.

In testimony whereof, I have signed my name to this specification, in the presence 90 of two subscribing witnesses.

HENRY W. O'DOWD.
